United States Patent Office

Des. 179,974
Patented Apr. 2, 1957

179,974

GUN

Jessie T. Ivy, Seattle, Wash.

Application May 14, 1956, Serial No. 41,486

Term of patent 14 years

(Cl. D30—1)

Fig. 1 is a side elevation of a gun embodying my new design as seen from the right hand side.

Fig. 2 is a side elevation of the same as seen from the left hand side.

Fig. 3 is a top plan view of the gun.

The essential features of the gun reside in the stock shown in full lines.

I claim:

The ornamental design for a gun, as shown and described.
